SAFETY DEVICE FOR ROTATING TOOLS

Filed Feb. 26, 1931

UNITED STATES PATENT OFFICE

ALBIN M. DEGNER, OF TOLEDO, OHIO, ASSIGNOR TO SURFACE COMBUSTION CORPORATION, OF TOLEDO, OHIO, A CORPORATION OF NEW YORK

SAFETY DEVICE FOR ROTATING TOOLS

Application filed February 26, 1931. Serial No. 518,322.

This invention relates to a safety device for rotatable collapsible taps and like tools which are reset by a radially extending lever carried by the body of the tap. The operator will frequently attempt to reset the tap while it is rotating especially when the tap is mounted in a drill press spindle. This is a dangerous proceeding since the operator's sleeve is liable to become entangled in the lever with serious consequences to the operator as will be readily appreciated.

In accordance with the present invention, the tool is encircled by a ring which is pivotally mounted on the body of the tool, the ring being coupled to the extending end of the actuating lever, the arrangement being such that when the ring is tilted the lever will be actuated.

Referring to the accompanying drawings, forming part of this specification,

Fig. 1 is a perspective view of a well known type of collapsing tap and showing the present invention applied thereto,

Fig. 2 is an enlarged vertical cross section taken on line 2—2 of Fig. 1;

Fig. 3 is a side elevational view of the device shown in Fig. 1;

Fig. 4 is a view partly in section and partly in elevation of the device shown in Fig. 1, the section being taken on line 4—4 of Fig. 3;

Fig. 5 is a transverse section taken on line 5—5 of Fig. 2;

Fig. 6 is a transverse section taken on line 6—6 of Fig. 2, and

Fig. 7 is a fragmentary view in cross section illustrating the arrangement of parts shown in Fig. 2 in locking relationship.

In the drawings, 11 designates a tap body having an integral tapered shank 13 for insertion in the spindle of a drill press, lathe or the like. The body is provided, at its lower end, with a number of equidistant radial slots 15 for the reception of cutters or chasers 17 which are held in place by a cap 19 fastened to the bottom face of the body. The cutters are adapted to be moved inwardly or outwardly from the axis of the body 11, as the case may be, by a plunger 21 having a head 23 in interlocking and sliding engagement with the cutters, as is clearly shown in Figs. 2

and 6. The plunger is normally held in retracted position by a spring 25, the upper end of which engages the underside of a nut 27 carried by the upper end of the plunger, and by which the cutters are held drawn into the body 11 a sufficient distance to clear the work.

The handle for depressing the plunger is shown as a laterally extending lever 29, pivoted as at 31 in a collar 33, and having an extending finger 35 the end of which projects into a suitable hole or cavity 37 in the body 11. The collar 33 is in sliding relation to a sleeve or ring 39 slidable on the body 11 and which is provided with a flange 41 against which the collar 33 bears. The sleeve 39 is coupled to the plunger 21 by means of a transversely arranged coupling bar 43 as is clearly shown in Fig. 5, it being noted that the body 11 is provided with a diametric clearance slot 45 long enough to permit the plunger and sleeve to have a conjoint movement sufficient to expand or collapse the cutters when the lever 29 is actuated.

In order to hold the cutters in expanded or set position there is provided a segmental detent 47 located within a transverse slot provided in the wall of the sleeve 39. This detent is normally held pressed against the inner wall of an annular flange 49, depending from a ring 51 adjustably mounted on the body 11, by a small spring 53 located in each end of the detent, the flange extending into an annular space formed between the upper ends of the sleeve 39 and collar 33. The bottom outside edge of the detent is formed with a chamfer and the bottom of the space in which the flange projects is formed with a bevel, so that, after the sleeve 39 has been depressed sufficiently to set the cutters, the detent will move outwardly until the beveled faces abut and the detent engages the underside of the flange 49 thereby locking the cutters in set position. To release the lock and collapse the cutters, the collar 33 is moved upwardly, either by the lever 29 or some other means, so that the beveled faces coact with each other to crowd the detent inwardly against the action of spring 53 until the detent disengages the flange 49 as will be readily understood.

From the foregoing description, it will be seen that when the apparatus is revolving, the laterally extending handle or lever 29 constitutes a source of danger to the operator, as by catching in his sleeve when he attempts to operate the handle. To eliminate this source of danger, the present invention provides a protecting shield or ring which permits the operation of the lever without danger to the operator.

In accordance with this invention, there is provided, as shown in Fig. 1, a shield or ring 55 which encircles the apparatus. The ring is pivotally mounted on a pair of laterally extending projections or spokes 57 of which the collar 33 forms the hub and is suitably attached to the end of lever 29 so that when the ring is tilted the lever will be operated. By providing the end of spokes 57 with screws 59 and the end of lever 29 with a screw 61, all of which extend through clearance holes provided in the ring and are screwed into their respective sockets until flush with the outside periphery of the ring, not only is a relatively simple pivotal mounting, which is easy to assemble, provided, but all danger from protruding screw heads is eliminated.

In order to prevent the laterally extending spokes and lever from catching the operator's fingers when he touches the ring to either set or collapse the cutters, there is provided within the ring 55 a shield 63. This shield preferably comprises a screen disposed within the ring above the spokes and lever so as to effectually prevent them from catching the operator's fingers without obstructing his view of the work. As will be readily appreciated from the foregoing description, the invention is in the nature of an attachment for a type of rotating tool now on the market and having a radially extending lever 29.

In certain types of work done by rotatable collapsing tools, it is desirable to automatically collapse the cutters after they have entered the work a desired distance. To this end there is provided a trip plate 65 which is supported at the end of a pair of adjustable arms 67 suitably attached to the collar 33. As soon as the cutters have entered the work the required distance, the work engages the trip plate and through the arms 67 causes the collar to move upward and thereby unlatch the detent 47, allowing the cutters to collapse as has heretofore been described.

55. What I claim is:

1. The combination with a rotatable tool having radially movable cutting elements and means including a lever rotatable with the tool for actuating said elements, of a ring encircling said tool and enclosing the lever and connected to the outer end of said lever, and means supported by said tool for pivotally supporting said ring for rotation with the tool.

65. 2. The combination with a rotatable tool

having radially movable cutting elements and means including a lever rotatable with the tool for actuating said elements, of a ring encircling said tool and enclosing the lever and connected to the outer end of said lever, means projecting from said tool for pivotally supporting said ring for rotation with the tool and a shield carried by said ring.

In testimony whereof I affix my signature.

ALBIN M. DEGNER.
